SELECTIVE VALVE OPERATING APPARATUS

Nathaniel R. Andrews, Yonkers, N. Y.

Application November 13, 1934, Serial No. 752,855

40 Claims. (Cl. 137—139)

This invention relates to a valve-operating apparatus particularly applicable for use in selectively operating valves such as ordinary gate or globe valves arranged regularly in manifold or "bank" formation and which are opened and closed by rotating the valve stem. The apparatus may, for example, be usefully employed in connection with sugar or oil refining machinery for the operation, from a point of remote control, of a single valve at a time or of a plurality of valves arranged in group form or in a bank and which may require, in some instances, selective operation, and in other instances, simultaneous operation.

15 The apparatus of my invention is adapted for general use and for various special uses, and in general comprehends a traveler, a rider on the traveler, and valve-operating means on the rider whereby to open or close one or a plurality of valves. The apparatus also comprehends means including electric glow lamp signals for indicating to the operator whether the valves are in open or closed position, and also involves means for indicating to the operator the relative position 20 of the valve-operating devices with respect to the valves in the bank.

25 Among the objects accomplished by the invention are the following:

To provide a horizontally operable traveler and a vertically operable rider, both electrically controlled, and through the control of the traveler and rider to locate the valve operating device before the valve, or group of valves, to be operated, within an allowable clearance. To automatically and accurately center the valve operating device and lock it in such position. To automatically adapt the valve operating device to the stem travel and seating requirements of the valve, or valves to be operated. To automatically open or close the valve, or group of valves, desired. To provide three electrical control switches with their circuits and so interlock the same that neither the traveler nor the rider can be moved or displaced while the centering, locking, or opening and closing devices are operative, and also vice versa. To provide means for allowing full torque of the opening and closing motor to be applied when starting the valve disk from its seat during the opening operation, or from contact with its proper travel stop during the closing operation of the valve; and to automatically adjust the torque to the desired amount for the seating of the valve while it is being closed, or if the valve is being opened, to 55 adjust the torque to the desired amount for prop-

erly stopping the disk holder against the body of the valve at the completion of the opening operation.

Other objects accomplished by the invention consist in the provision of mercury governor means for limiting the speed of operation of the valve-operating device, and the provision of means whereby at the completion of both the opening and closing operations of the valve, or group of valves, to free the operating device in such manner that the strain in the gear train will be relieved for easy withdrawal or disconnection of the valve operating device.

Provision is also made whereby at the completion of the operation for opening or closing a valve, or group of valves, all of the electrical circuits will be "cleared", and further whereby, after the opening or closing of a valve, or group of valves, all mechanical parts will be restored so that the operator may begin the next cycle 20 of operation, i. e., the next valve operation that may be desired.

Although in the present illustrative embodiment of the invention, there is shown a group or bank of valves consisting of horizontal and vertical rows, it is to be understood that with proper adaptations in the parts of the apparatus, which adaptations may be made without any change in operative principle, the valves may be inclined as to the positions thereof or 30 they may be arranged on a cylindrical or curved surface. The valves to be operated may be of various sizes, may have different ranges of travel, and may require different seating pressures. The apparatus automatically adjusts itself in these 35 respects to the duties to be performed, seating the valve disk on its seat with the proper pressure for the size of the valve which it is operating. The speed control means which is employed allows the use of a series motor with its 40 advantage of high starting torque. When the valves are arranged for group operation, each group may include two or more different sizes of valves, and the groups in the bank may differ in respect to valve sizes and in the order of the 45 arrangement of the valves. The groups may also differ as to the number of active valves in each group.

While in the present embodiment, I have shown an example of the invention having two duplicate valve-operating devices, only one of which is illustrated in detail, it is to be understood that any number of similar valve-operating devices can be employed in an apparatus designed for such purpose, as this does not affect the principle 55

of the invention. The present invention will be more readily understood by reference to the following description in connection with the accompanying drawings, showing one example of the invention, and the invention is not to be considered as limited thereby in any respect. The full scope of the invention will appear after an understanding of the illustrated embodiment and an appreciation of the advantages the invention produces therein.

It is to be understood that various additional objects not specifically enumerated above, are inherent in the invention and these will appear to one skilled in the art as the following specification proceeds.

Referring now in brief to the drawings, where-in similar characters of reference denote corresponding parts throughout the several views:—

Figure 1 is a side elevational view, parts being broken away, of a selective valve-operating apparatus produced according to the invention;

Fig. 2 is an end elevational view and section, looking toward the right-hand end of Fig. 1;

Fig. 3 is a side elevational view of the accurate centering and locking mechanism for the rider;

Fig. 4 is a cross sectional view taken on the line 4—4 of Fig. 3;

Fig. 5 is a cross sectional elevational view of the accurate centering and locking mechanism 30 for the traveler, this view being taken on the line 5—5 of Fig. 1;

Fig. 6 is a cross sectional view taken on the line 6—6 of Fig. 1 and showing in side elevation and detail one of the valve operating devices or units 35 in association with a wheel valve, certain of the parts being broken away to show the next adjacent valve-operating device and wheel valve when looking in the direction of the arrows associated with said section line 6—6.

Fig. 7 is an elevational view, more or less diagrammatical in character, showing a group of valves to be operated, some members being of a size different from other members, the group comprising three horizontal rows and three vertical rows;

Fig. 8 represents merely for the purpose of illustration, a characteristic control station, showing signal lamps for indicating the opened and closed positions of the valves shown in Fig. 7, 50 showing dials for the traveler and rider marked to correspond with the valves, and showing also the interlocking control switches;

Fig. 9 diagrammatically illustrates an arrangement of the interlocking circuit connections for 55 the control switches;

Fig. 10 is a diagram showing the relation of the circuits and electrical devices of the driving motors for the traveler and rider, respectively;

Fig. 11 is a characteristic diagram of the electrical illuminating connections for the mercury switches the movements of which are controlled by the operation of their corresponding valve-operating devices;

Figs. 12 and 13 diagrammatically illustrate by 65 successive portions the arrangement of circuits and electrical devices for the accurate centering and locking mechanisms and for the two valve-operating devices.

Describing the invention with reference to the 70 drawings, in which I have shown two corresponding valve-operating devices supported for operation upon a rider which in turn is operatively supported upon a traveler, it will be seen that the framework of the traveler, designated as a whole 75 by 20 and which is illustrated as an upright or

vertical structure, is mounted on the wheels 21 and 22 which turn on a horizontal track rail 23. The wheel 22 comprises the traction wheel and it is driven by an electric motor 24 through magnetic coupling 26, gear reducer 25, belt 27 and 5 pulley 28. The motor 24 and gear reducer 25 are mounted upon a platform 28' located immediately above the traction wheel 22. The magnetic coupling 26 is on gear reducer driven shaft 26^a, the same being incorporated in said shaft between 10 the gear reducer and pulley 26^b which drives the belt 27. Mounted for vertical sliding movement in suitable guides 28'' in the traveler framework 20, is the rider frame 29. Attached to the rider frame 29 are cables 30 and 31 which are trained 15 over the traction sheave wheels 32 and 33, respectively, said cable 31 being also trained over an idler sheave wheel 34. Below the sheave wheels 32 and 33, these two cables are attached to a counterbalancing weight 35 which is slidably engaged with a vertical flange 35' provided for the purpose on the traveler framework. Traction sheaves 32 and 33 are mounted on a common shaft 36, free to turn on a suitable bearing in framework 20, and they are driven by an electric motor 37 through gear reducer 38, magnetic coupling 39, belt 40 and pulley 41. The motor 37 and gear reducer 38 are supported upon a suitable platform 41' projecting from the framework 20 at the upper end thereof over the platform 28'. 30 The magnetic coupling 39 is incorporated in gear reducer driven shaft 39^a, between the gear reducer and the pulley 39^b which drives the belt 40.

To the underside of an extension 42' of the traveler framework 20, which projects adjacent 35 to and beyond the travel wheel 21, there is secured a motor 42 which comprises the transmitting motor of a conventional "selsyn" set. The rotor of this motor 42 is rotated by means of a pinion 44 which is in engagement with a stationary gear rack 45 disposed adjacent to and parallel with the track rail 23. The reduction ratio of gear reducer 43, which is supported from extension 42' and interposed in the transmission line between the pinion 44 and the motor 42, is 40 such that the maximum travel permitted the traveler 20 in either direction produces less than one revolution of the motor 42. Another motor 46 and its gear reducer 47 are rigidly mounted on the rider frame 29. This motor also comprises 45 the transmitting motor of a "selsyn" set and its rotor is rotated by a pinion 48 engaged with a vertically extending gear rack 49 mounted on the traveler framework 20. The reduction ratio of the reducer 47 is such that the maximum travel 50 of the rider relative to the traveler produces less than one revolution of the motor 46.

For the traveler and rider accurate centering and locking mechanisms are provided in order to adjust, secure and maintain these parts in the 55 desired positions for aligning the valve operating devices presently to be described, with the valves which are to be operated thereby. The accurate centering and locking mechanisms are shown in general in Figs. 1 and 2 and in more detail in 60 Figs. 3, 4 and 5. Figs. 3 and 4 illustrate the accurate centering and locking mechanism mounted in vertical position on the rider 29 while Figs. 1 and 5 show a corresponding mechanism mounted in horizontal position on the traveler 20. Referring first to Figs. 1, 3 and 4, it will be seen that the hub 50 of the bell crank 51 is free to turn in a bearing 52 which is rigidly mounted on the frame of rider 29, and that said hub is restrained 65 from longitudinal movement by a collar 53. A 70

shaft 54 extends through the hub 50 and is free to move longitudinally therein, but is restrained from rotating independently of the hub 50 by means of its longitudinally extending key or projection 55 which has sliding fit in a key-way or slot in the hub 50. To said shaft 54 are rigidly fastened the solenoid plunger 56, an arm 57 and a collar 58. Said shaft 54 is free to move both longitudinally and rotatively in solenoid coil 59 and in bearing 60, both being rigidly fixed to rider frame 29. A spring 61, coiled loosely about the shaft 54, is imprisoned between and exerts pressure against collar 58 and bearing 60. The housing 62 of the solenoid coil 59 and the housing 63 of another solenoid coil 64 are both rigidly fastened to the rider frame 29. To the plunger 65 of solenoid coil 64 is securely fastened a rod 66 which is pivotally connected at 66^a with one arm of the bell crank and which, when the solenoid 64 is energized, moves the bell crank 51 against the action of a spring 67 fastened at one end to the rider frame and at the other end to the bell crank arm at 67^a. A contact bar 68, secured to but electrically insulated from the plunger 65, is adapted, when the plunger is drawn into the coil, to make contact with the two contact points 69 which are supported by, but electrically insulated from, the solenoid housing 63. A contact bar 70 secured to but insulated from plunger 56 is adapted, when plunger 56 is drawn into the coil 59, to make electrical contact with contact points 71.

As has been observed, the arm 57 is fixed to the shaft 54, and the bell crank 51 is so keyed to said shaft that its other or free arm 72 lies opposite to and parallel with the arm 57. In this relationship the two arms 57 and 72 are turned together with the turning of the shaft. Now, the traveler frame is provided with a vertical row of spaced-apart stop pins 73, each of which as we presently shall observe, corresponds as to elevation with a valve or valves to be operated. When or while the rider is being raised or lowered, the two solenoids 64 and 59 being deenergized, arms 57 and 72 are in such positions that they escape engagement with the pins 73; but when it is desired to interlock the rider with any selected pin, the solenoid 64 is energized when the rider is in that position in which the two arms 57 and 72 will be swung into positions at opposite sides of the selected pin, whereupon, upon the energization of the other solenoid 59, the shaft 54 will be moved longitudinally until the two arms clamp against the solenoid pin from opposite sides thereof with the result that the rider will be locked in the position selected until the two solenoids are again de-energized.

The accurate centering and locking mechanism on the traveler is in construction and operation a substantial duplicate of the mechanism on the rider which has just been described for interlocking the rider with a selected pin 73, except that on the traveler, such mechanism is mounted in horizontal position so as to interlock the traveler with any one of the pins 73' arranged in spaced relation in a horizontal row parallel to the track rail 23. Since this accurate centering and locking mechanism on the traveler is a duplicate, it seems unnecessary to describe the same in detail, but only to point out by reference to Figs. 1 and 5, that it includes arms 57' and 72' for engaging against opposite sides of a selected pin 73'. The arm 57' is rigid with the shaft 54' while the arm 72' is part of a bell crank the hub of which is keyed on said shaft, its other arm being pivotally connected through rod 66' with the plunger

65' which cooperates with solenoid coil 64' in housing 63'. The plunger 65' carries an insulated contact bar 68' for cooperating with the contact points 69', and moves against the action of a spring 67'. The solenoid 62' contains a coil for 5 cooperating with the plunger 56' fastened to the shaft 54' which moves longitudinally against the action of spring 61'. From the end of the plunger 56' there is supported an insulated contact bar 10 70' which makes contact with the contact points 71' when the plunger is drawn into the solenoid coil. When the coils of both solenoids 62' and 63' are energized, the arms 57' and 72' will be moved into interlocking engagement with the selected pin, the traveler having of course, prior to the 15 energization of the solenoids, been moved into that relation with the selected pin which will permit interlocking engagement therewith by the two arms 57' and 72'. The horizontal spacing of 20 the pins 73' correspond with the horizontal spacing of the valve or valves to be operated, as will presently be made manifest.

The traveler is guided at the top by the overhead stationary guide rail 74. A sufficient number of trolley wires 75, two only being shown, 25 with their corresponding trolleys 76, and a sufficient number of contact rails 77, two only being shown, with their corresponding trolley or contact arms 78, are provided to convey the necessary 30 electrical current to the devices requiring current for their operation and which are mounted on the traveler frame 20. Also a sufficient number of trolley wires 79, two only being shown, with their corresponding trolleys 80, are provided to convey the necessary electrical current from the traveler 20 to the electrically operated devices mounted on the rider 29. 35

The valve opening and closing devices or units will now be described in detail. In the present embodiment only two of these devices or units 40 are shown, respectively indicated as a whole in Fig. 1 by the reference characters 201 and 201'. These devices or units are individually mounted upon the rider frame 29 transversely thereof, and it will be observed that in the present embodiment they lie in planes at right angles to the plane of the rider. Inasmuch as these devices or units 201 and 201' are duplicates, a detailed description of the former will also suffice for the latter, although in describing the interlocking electrical circuits and connections for 45 these devices it may sometimes be necessary to refer to parts of the device or unit 201' and for purposes of convenience and identity, such references will be made in the prime terms of the 50 numerals employed in describing the device or unit 201.

Referring now to Fig. 6, it will be seen that the hub 203 of the bevel gear 202 is mounted for free rotation in a bearing in the framing or unit 60 201, and is restrained from longitudinal movement therein by the collar 204. The shaft 205 is provided with a longitudinally extending key or projection 206 which fits in a corresponding slot or keyway in the hub 203 of the bevel gear 65 202. The shaft 205 with its key 206 is free to move longitudinally in the hub 203, but the rotation of the bevel gear 202 causes the shaft 205 to rotate with it. To the shaft 205 is fastened a collar 207 having an annular flange 208. A 70 coil spring 209 fits loosely around the shaft 205 and exerts pressure against the hub 203 and the collar 208. To shaft 205, which is preferably of non-magnetic material, is fixed the soft iron plunger 210 which is free to move longitudinally 75

and rotatively within the solenoid coil 211. The housing 212 of the solenoid coil 211 is rigidly fastened to the framework 201. One end of the shaft 205 terminates in a fork 213 while the other end thereof is free to move longitudinally and rotatively in a bearing 214 provided in the framework 201. A vertically disposed electric motor 215 is rigidly fastened to the framework 201 and to the lower end of the driving shaft 216 of this motor is keyed a bevel gear 217 which meshes with the bevel gear 202. To the upper end of shaft 216 is keyed a gear 218 which meshes with a relatively large gear 219, and this last-named gear is keyed to a shaft 220 which is free to rotate in a bearing of the framework 201. The upper end of the shaft 220 is centrally and rigidly fixed to the circular bottom of a cylindrical cup-shaped shell 221. Within this cup-shaped shell, which is preferably of non-magnetic material, are disposed mercury contactors 222 and 223 which are rigidly supported in inclined positions by means of suitable clips 224 and 225, respectively, these clips being rigidly fastened to the shell 221. Each terminal of the mercury contactors is electrically connected to its individual slip ring 226. The several slip rings 226 are electrically insulated from one another, each having its individual contact brush 227, and in this connection it is to be observed that the several brushes 227 are electrically insulated from one another and from the framework 201 which supports them.

A rod 228 of square cross sectional form is rigidly fastened at one end to the framework 201 and at the other end to the solenoid housing 212. A square hole in the sliding member 229 receives therethrough with sliding fit the guide rod 228, so that said member 229 may move longitudinally along the guide rod 228. The arms 230 of the sliding member 229 comprise a fork which engages with the flange 208 in such manner that a longitudinal movement of shaft 205 will produce a corresponding movement of the sliding member 229 with its integral upwardly extending arms 231 and 232. The feeler 233 is a rod of square cross sectional form, free to slide lengthwise in square holes in framework 201 and the arm 232, and is provided with collars 234 and 235. A coil spring 236 fits loosely about feeler 233 and exerts pressure against collar 234 and framework 201. To the collar 235 are fastened contact points 237 and 238, electrically insulated from said collar and from each other. These contact points make electrical contact with the contact plate 239 which is fastened to, but electrically insulated from, the arm 232. Feeler 240 is a rod of square cross sectional form, free to move lengthwise in square holes in framework 201 and in arm 231, and it is provided with collars 241 and 242. A coil spring 243 loosely surrounds feeler 240 and exerts pressure against collar 241 and arm 231. A rod 245 in longitudinal alignment with the rod 240 is guided by, and slides in, a bearing in the arm 232, and it is provided with collars 246 and 247. A coil spring 248 loosely surrounds rod 245 and exerts pressure against arm 232 and collar 246. To the face of collar 242, but electrically insulated therefrom, is fixed a contact plate 244, and likewise to the adjacent face of the collar 246 is fixed a contact piece 249. The feeler 250 is a rod of square cross section, free to move with a sliding fit through square holes in framework 201 and arms 231 and 232. This feeler 250 is provided with collars 251 and 252. A coil spring 253 surrounding this feeler

exerts pressure against collar 251 and arm 231. To feeler 250 are fixed the contact strips 254, 255, 256 and 257, which strips are electrically insulated from the feeler 250 and from each other. These contact strips 254, 255, 256 and 257 may make electrical contact with the series of contact points 164, 165, 166 and 167, respectively. These contact points 164, 165, 166 and 167 are supported by, but electrically insulated from, the framework 201. Stops 258, 259 and 260 are provided for rods 233, 240 and 250, respectively. These stops are mounted for longitudinal adjustment in a stationary support 261. A rod 262 of square form in cross section which slides longitudinally in suitable guides provided in the stationary support 261, is made at one end with a fork 262a, which is engaged with a rim of the valve hand-wheel 263. On the opposite end of rod 262 spaced tappets 264 are provided for the purpose of tilting the arm 267 carrying a mercury switch 265, said arm being pivoted at 265a to the stationary support 261.

A pair of glow lamps 266 are electrically connected with the two terminals 266a, respectively, within the mercury switch, and electrically connected terminals 266b having connection with a current supply line, are arranged in the usual way within the switch with relation to the terminals 266a to cause one or the other of the lamps 266 to glow, accordingly as the switch is tilted in one direction or the other to flow the mercury and complete the circuit. Thereby, when the valve is in open position, one of the two lamps will be caused to glow; and conversely, when the valve is in closed position, the other of the two lamps will glow. The dotted position of hand-wheel 263 and fork 213 indicate their position when the valve 263 is closed. In Fig. 6, a portion 213' of the companion closing device is shown, and also a portion 263' of the valve-wheel to be operated thereby, portions of the fork 213 and of the valve 263 being broken away in order to exhibit the portions 213' and 263' of the valve-operating device and valve wheel adjacent thereto and next in line.

From an inspection of Fig. 1, it will be evident that the motor-operated traveler is movable horizontally in either direction upon a track before a series of valves arranged in bank in vertical and horizontal rows. It will also be evident that the motor-operated rider is movable vertically up and down relative to the traveler and may carry one or more, electrically operated devices for actively engaging the valve, or valves, with which it, or they, are aligned, to open or close the same. Through the relative movements of the traveler and rider, the valve-operating devices may be located before the valve or group of valves to be operated, within an allowable clearance, and through the centering and locking mechanisms on the traveler and rider, respectively, in cooperation with the stop pins which serve both as accurate stop centers and locks, the valve-operating devices can be accurately aligned with respect to the valves to be operated thereby, and held against displacement in any direction from such accurately aligned position because the effective interlocking engagement which takes place with the pins by both the traveler and rider positively prevents any displacement of the traveler horizontally in either direction and any displacement of the rider vertically in either direction. It will, of course, be understood that the pins 73 and 73' are so located that when they are engaged by the center-

ing and locking mechanisms, as above described, the valve-operating devices will be accurately centered and locked in the proper position for engaging the wheel of the valve, or valves, to be opened or closed.

In order to give an example of the utility of the invention in connection with a remote control station having means for indicating to the operator the status of a group of valves composed 10 of more than two vertical and horizontal rows, I have shown in Fig. 7, a group or bank of valves arranged in horizontal rows Ha, Hb and Hc and vertical rows Va, Vb and Vc; and in Fig. 8, a remote control station in the form of an operator's 15 panel Op having pairs of signal or glow lamps arranged in horizontal rows Ha¹, Hb¹ and Hc¹, corresponding relatively and respectively to the horizontal rows of the valve bank, and also in vertical rows Va¹, Vb¹ and Vc¹, corresponding relatively and respectively to the vertical rows of the 20 valve bank. It will be evident that for each valve in the bank a pair of signal lamps which correspond with the pair of lamps 266 in Fig. 6, is provided in order to have means whereby to 25 show when each valve is in open position and when the same is in closed position.

On the operator's control panel Op, two dial indicators 130 and 131 are illustrated the purpose and object of which are to show, oy or through 30 the traveling movements of the rider and traveler, respectively, the position of the valve-operating devices 201 and 201' relative to the valves which are to be operated thereby.

The index hand 132, with which the indicator 35 130 is equipped, is driven by the receiving motor (not shown) electrically connected to motor 46, the transmitting and receiving motors of which comprise a conventional "selsyn" set that is to say, a set of self-synchronizing motors, as will be 40 readily understood. Similarly the index hand 133, furnished on the indicator 131, is actuated by means of transmitting motor 42 and its receiving motor (not shown). The position of the hand 132 relative to the dial markings Ha², Hb² 45 and Hc² on the dial of the indicator 130 indicates the relative position of the valve-operating device to the horizontal rows Ha, Hb and Hc of the valve bank. Similarly, the position of the hand 133 relative to the markings Va², Vb² and 50 Vc² on the dial of the indicator 131 indicates the relative position of the valve-operating device in respect to the vertical rows Va, Vb and Vc of the valve bank.

On the operator's control panel Op, three manually operated control switches, A, B and C, are also mounted. Referring to Fig. 9, it will be seen that the blades of the switches A, B and C, are each provided with two contact bars. Thus, the blade of switch A carries the first and second 55 contact bars A', A''; the blade of switch B carries similar bars B', B''; and the blade of switch C carries similar bars C' and C''. The second contact bars, A'', B'' and C'', are fastened to, but electrically insulated from, their current carrying blades, as clearly shown in this figure. The 60 normal position of these switches is that shown by the full lines. Switches A and C are automatically returned to their normal position, being actuated by springs (not shown), when released 65 from the pressure of the hand of the operator. Switch B, likewise, is returned from the dotted positions shown to its normal position, but only when the circuit which has been established in one of the holding coils 134 and 135 has been 70 broken by means later to be described. The three 75

switches are so electrically interlocked that switch B, in the dotted positions shown, is operative electrically only when both switch A and switch C are in their normal positions, and neither switch A nor switch C, when moved to its respective dotted positions as indicated, is electrically operative unless switch B is in its normal position.

At this point it is desired to point out that the operator's control station or panel Op with its 10 signal lamps, its two position indicators, and its three control switches, may be located remote from the valves to be operated. The position of the index hands of the indicators relative to the reference characters on the dials thereof, indicate at all times the position of the valve-operating devices 201 and 201', relative to the valves in the bank. In the present embodiment switch A controls the forward and reverse movement, horizontally, of the traveler; switch C, the up and down vertical movement of the rider; and the remaining switch B, the operation of the accurate centering and locking mechanisms as well as the operation of the valve-operating devices for the opening or closing of the valve, or group of valves, 25 desired. The two electric lamps 266, which are provided for each valve, or group of valves, are preferably of different color. One of these, when glowing, indicates the open, and the other, when glowing, the closed, position of the valve, or all of 30 the valves in a group. These pairs of lamps, as has been observed, are arranged diagrammatically to correspond to the position of the valves in the bank. The operator, guided by the position of 35 the index hands of the indicators or position-indicating devices, manipulates the two switches A and C controlling the horizontal movement of the traveler and the vertical movement of the rider, and in consequence roughly locates or centers the valve operating devices before the valve, or group 40 of valves, selected for operation. By placing the third switch B in the "opening" or "closing" position, the operator then causes the accurate centering and locking mechanism to function and the valve to be opened or closed as desired, the 45 completion of the operation being indicated by the panel signal lamps. After the apparatus has been centered by the operator within an allowable tolerance, as indicated by the position-indicating devices, and the switch B manually arranged to 50 "open" or "close" the valve or group of valves desired, the remainder of the operation of accurate centering and locking, the actual manipulation of the valve or valves, the clearing of the electrical circuits, and the return of all mechanical parts to 55 a position in which the apparatus is in readiness for the next operation, is entirely automatic.

The valves to be operated are arranged in spaced groups and two (or more) of the valve-operating devices such as is shown in detail in 60 Fig. 6, are mounted on the rider 29. The electrical circuits shown in Figs. 9, 10, 11, 12 and 13 may be arranged for the operation of the valves in groups of two, but it will be understood that the apparatus may be constructed to operate more 65 than two valves in a group, if desired. For simplicity of description, direct current is indicated, although alternating current can be used as well. Alternating current is of course required for the 70 operation of the "selsyn" sets.

In the illustrated circuit diagrams, contactors which are re-set by re-set coils, are shown in the re-set or closed position. Contactors which are drawn into contact position by the action of coils which hold them in this position only when ener-

gized, are shown in the normal or open circuit position.

In the electrical circuit shown in Fig. 10, 24a and 24b are the armature and field, respectively, of the motor 24, and 24' is the solenoid coil of the magnetic coupling 26 associated with the motor 24. 37a and 37b are the armature and field, respectively, of the motor 37, and 37' is the solenoid coil of the magnetic coupling 39 associated with the motor 37. The solenoid or magnet coils 136, 137, 138, 139, 140, 141, and 136', 137', 138', 139', 140' and 141', which are energized by the placing of the switches A and C in the positions indicated by dotted lines in Fig. 9, are all indicated with their associate contactors or relays in Fig. 10. The normal position of the contactors which is the position to which they return when the coils are de-energized, is the open position. It will be seen that when either of the coils 24' or 37' of the magnetic couplings is energized, the solenoid coil 143 will also be energized to close its associated contactor. This operation will cause the flow of current in the re-set coils 156, 157, 158, 159 and 156', 157', 158' and 159', thus re-setting the contactors shown associated with these coils in the circuits of Figs. 9 and 13.

In order to trace through a cycle of operation, let us assume that the operator has roughly centered the valve-operating device or devices, before the valve, or group of valves, as shown in Fig. 1, and has moved the switch B so that the coils 148, 348 and 162 (Figs. 9, 12 and 13) are energized and let us assume further that this is the position for closing the valve, or valves. Now the coil 148 causes the contactor associated with it, normally open as shown in Fig. 13, to close. Current now flows through the solenoid coil 64 and swings arms 57 and 72 into position for engaging the stop pin and also brings contact bars 68 into electrical contact with the points 69. This energizes coil 59 and causes arm 57 to approach arm 72. The rider 29, being counterbalanced and now disconnected from the motor 37 and the reduction gear 38 since the magnetic coupling coil 37' is de-energized, is moved by the action of the arm 57 against the pin 73 until arms 57 and 72 assume the position shown in Fig. 1. The rider is now so located that the valve-operating devices are accurately centered relative to the horizontal row of valves desired, and remain locked in this position, until the valve or valves in the group are closed. In a similar manner, the traveler 20 is accurately centered and locked on a stop pin relative to the vertical row desired. When the centering and locking of both the traveler and the rider have been completed, the solenoid coil 143x (Fig. 12) closes its associate contactor, and the solenoid coil 211 of the valve-operating device is also energized. So also is the coil 211' of the companion valve-operating device. The fork 213, and as well the fork 213' of the companion device, move forward and the prongs of the forks engage the spokes of the wheels of the valves which are to be opened.

In Figs. 12 and 13, circuits are shown for two valve-operating devices 201 and 201'. Since these circuits and devices are alike, one only will be described. When the contactor associated with coil 143x is closed, current will flow in the armature 215a and the field 215b of the motor 215, by way of the contactors associated with coils 150, 154, 156, 157, and 151, respectively, and the mercury switch 222, it being understood that the maximum speed of the motor will be controlled by the action of the mercury in the

switch 222, which action causes the circuit to be broken intermittently at a predetermined speed, fixed by the angle of the switch with respect to the vertical, the amount of mercury in the tube, the distance of the tube from its axis of revolution, and the gear ratio of the train of gears between the cup 221 and the motor 215. Now, when the feeler 240 abuts against the stop 259, contact will be made between the contact bars 244 and 249, and this will result in energizing the solenoid coil 154 and cause the contactor associated with it to close the circuit through its upper contact points. The current will now reach the motor 215 through the resistance 145, all or in part, through all or part of the solenoid tripping coil 144, the latter being the tripping coil for the contactor shown associated with re-set coil 156, and through mercury switch or governor 223 which is set at a greater angle with respect to the vertical than switch 222, and consequently the maximum limit of the speed of motor 215 is less when current flows to it through switch 223 than when it flows through switch 222.

The amount of resistance 145 in the circuit and the strength of the tripping coil 144 depend upon the position of the contact bars 255 and 254 relative to the points 165 and 164, respectively, and this position is fixed by the adjustable stop 260 against which the feeler 250 abuts as it is carried forward by the sliding member 229, and in this connection the spring 253 is so designed that its compression is negligible until feeler 250 comes in contact with stop 260. It is readily seen that by the use of mercury switch 223 and the variable resistance 145 that the valve disk may be "inched" down to its seat as slowly as desired. As the valve disk comes into contact with its seat, the current increases and the tripping coil 144 adjusted to proper strength, trips the contactor shown associated with re-set coil 156 when the torque reaches the value proper for the valve in question. It should be noted here that coil 147 is the tripping coil for the contactor associated with tripping coil 157 and 45 that said contactor and the contactor associated with tripping coil 156 are so mechanically connected that the tripping of either contactor effects the tripping of both. The tripped contactors, associated with tripping coils 156 and 157, 50 now complete circuit through their lower contact points, and cause a momentary reversal in rotation of the motor 215, the current in this case passing through coil 160 which is tripping coil for the contactor shown associated with the re-set coil 158 and which is adjusted to trip the contactor at just sufficient value of current to move the motor armature slightly, thus freeing the strain on the gear train and allowing the fork 213 to withdraw freely from the valve 60 wheel. The contactor tripped by coil 160 makes circuit through its lower contact points and energizes coil 161 which trips the contactor shown associated with it in Fig. 9. This action, when the contactor associated with 161' of the companion circuit is also tripped, de-energizes holding coil 134 and causes the return of switch B to its normal position. All electrical circuits are now "cleared" and the apparatus is ready for the next cycle of operation. The closing of the 70 valve, or valves, has been indicated to the operator by the glowing of the signal lamp on the panel of the operator's station.

The operation of opening a valve being so similar to the operation of closing, which has just 75

been described, and being easily traced on the electrical diagrams, it is not thought necessary to describe the same in detail.

While in the description the apparatus has 5 functioned to close, or open, two valves of a group, it will be evident that it is possible to change the circuits so that, with the valves so arranged that similarly positioned valves in the various groups are to be opened, and others relatively to each other similarly situated in the various groups, are to be closed, the apparatus 10 may be made to open certain valves of a group and close certain others at the same time. It will also be clear that if stationary or "dummy" 15 wheels be substituted in lieu of the regular valve, or valves, in any group, that the device will function if the number of regular valves be not the same in all of the groups.

This apparatus, as shown in the drawings, is 20 arranged for the operation of a valve in which the wheel is fastened to the valve stem and rises with it. For the operation of rising stem gate valves, the prongs of the fork 213 should be made longer, with the center of the fork bearing 25 upon the end of the stem. The prongs of the fork are made longer, in this case, so that they slide on the spokes at right angles to the plane of the wheel as the wheel is rotated to open or close the valve. The length of the prongs should 30 be greater than the maximum travel of the longest valve which the apparatus will be called upon to operate for this type of valve.

It is in place to remark here that instead of 35 using a feeler connected for operation as herein shown and described in order to short circuit resistances and vary the strength of the tripping coils, one feeler may be employed for changing resistances only, and another feeler, similar in all respects, for varying the strength of the tripping coils, each of these feelers being provided 40 with its individual adjustable stop associated with each valve.

It may also be observed that instead of using 45 solenoids to directly move the parts of the accurate centering and locking mechanisms and to impart axial movement to the valve operating shaft with its forked end for engaging the valve, these parts may be actuated by the use of cylinders and pistons, operated either by air or hydraulically, suitable motor driven pumps or compressors being mounted on the traveler and rider for supplying the pressures required, and suitable valves for controlling the action of said devices being provided and controlled from the operating circuits substantially as illustrated 50 herein.

Contactors, for instance mercury switches, may be employed to operate relay circuits instead of carrying the full operating current as shown.

The necessary alternating current source of 60 power including circuits for connecting the transmission and receiving motors of the "selsyn" sets have not been shown here, since the operation of such devices is well known. While series motors 65 have been illustrated, it will be recognized that compound wound motors may be used if desired. Also it will be appreciated that starting resistances could be inserted in the motor circuits if required and that control switches A, B and C 70 could be modified to progressively cut out such resistances.

It will be understood that the terms and expressions which I have employed are used as 75 terms of description and not of limitation, and I have no intention in the use of such terms and

expressions, of excluding any equivalents or counterparts of the features shown and described or portions thereof, but recognize that various modifications are possible. Moreover, as many changes could be made in the above construction 5 and in the operative circuits and many apparently widely different embodiments of this invention could be made without departing from the spirit or scope thereof, it is intended that all matters contained in the above description or shown in 10 the accompanying drawings shall be interpreted as illustrative and not in a limiting sense.

I claim:—

1. Selective valve operating apparatus comprising an electric motor operated valve operating device, an electric motor operated means on which said device is operatively supported, having guided movement to and from a position in which said device will be in alignment with a selected valve to be operated thereby, and a remote control for said motors including a distant station connected through electric circuits with said motors and having control switches. 15

2. A selective valve operating apparatus comprising an electric motor operated valve operating device, means on which said device is operatively supported including a horizontally movable part and a vertically movable part, electric motor operated means for causing movement of said parts to respective positions in which the 20 device will be roughly centered with respect to a selected valve which is to be operated thereby, electric motor operated locking means for said parts adapted on the locking operation thereof 25 to position said parts at the locations accurately 30 centering said device with respect to such valve and which are operative to lock said parts at the locations of accurate centering, a remote control for said motors including a distant station 35 having control switches, and circuits for the motors extending to and operable by the switches. 40

3. A selective valve operating apparatus comprising an electric motor operated valve operating device, path-guided movable means on which said device is operatively supported, an electric 45 motor on the supporting means for causing movement of said supporting means for roughly centering the device with respect to a selected valve which is to be operated thereby, a separate electric motor on the supporting means controlling 50 means for further moving the supporting means to establish accurate centering of the device with respect to such valve and including means constituting a part thereof for locking the supporting means in accurately centered position, a distant station, electric circuit connections between the station and aforesaid electric motors including control switches at the station, certain of said circuits being interlocked and adapted to be rendered effective for permitting operation of 55 the device for operating the valve only when said device is accurately centered.

4. The combination with a shaft having longitudinal and rotary movements, of means for moving the shaft longitudinally, an electric motor 65 for rotating the shaft, a pair of feelers movable by the longitudinal movement of the shaft, stops individual to the feelers for engagement thereby, a normally open circuit for the motor, contacts on one feeler forming part of the circuit and arranged to close the circuit when the feeler 70 engages its stop, bridging contacts on the other feeler forming part of this circuit and which are associated with contacts of series resistance coils and tripping coils for varying the resistance and 75

varying the strength of the tripping coils when this feeler engages its stop, and a governor rotated by the motor including mercury switch means incorporated in the circuit to intermittently break the circuit at a predetermined speed of the motor for regulating the rotation of the shaft.

5. In combination, a valve operating device having a connected electric motor adapted, when 10 operated, to operate the device, a guided traveling frame supporting said device and its motor and having a connected electric motor adapted, when operated, to cause the travel of the frame, a remote station including switch mechanism, 15 electrical systems associated with the switch mechanism including a line extending to the driving motor for said device and a line extending to the motor for said frame, said lines being interconnected to establish flow of energy for 20 operating the motor for said device when the switch mechanism is in one position and for establishing flow of energy for operating the motor for said frame when the switch mechanism is in another position.

25. 6. A positioning mechanism comprising in combination with a driven traveling frame and a driven valve operating shaft thereon having longitudinal movement, electric motors individual to the frame and shaft for driving the same, 30 magnetic means for moving the shaft longitudinally, an electric system for controlling the motors and magnetic means comprising a plurality of transmission circuits having interconnecting means for making and breaking the circuits, means for altering the relation of the interconnecting means and motors, and means for 35 altering the relation of the shaft driving motor in accordance with the longitudinal position of the shaft.

40. 7. The combination of a guided traveler, a guided rider thereon, mechanism for locking the traveler at a selected position along the course of its travel, mechanism for locking the rider at a selected position within the range of its 45 movement, driving electric motors individual to the traveler, the rider, and the two locking mechanisms, a system including a plurality of transmission circuits for the motors, a remote station including a plurality of switches manually operative from their normal or non-voltage positions to their circuit-closing positions, said circuits extending to the switches and having interlocking arrangement of such character that the switches when moved to their circuit-closing positions control the operation of the motors at 50 designated times and which are adapted thereupon to automatically return to their normal or non-voltage positions.

55. 8. The combination with a shaft having longitudinal movement and rotary movement, an electric motor for driving the shaft, an electromagnetic operator for imparting longitudinal movement to the shaft, a control switch, circuit connections for the motor and operator extending to the switch and which are adapted to be closed to actuate the motor and operator by the closing of the switch, said motor and operator being connected at one side of the circuit in series, a device in connection with the circuit between 60 the operator and motor adapted to be operated for breaking and making the circuit, and means under the control of the longitudinal movement of the shaft controlling the operation of said device.

70. 9. A selective valve operating apparatus com-

prising a valve operating device, frame means on which said device is operatively supported movable into and out of a position in which said device will be centered with respect to a selected valve to be operated thereby, said device having 5 a relatively movable part for operating a valve, electric motors individual to the frame means and the valve operating part, a remote station having control switches, circuits for the motors having association with the switches and having interlocking arrangement adapted to render one motor inactive when the other is active, and make and break devices in the motor circuit for the valve operating part controlled from the movement of such part.

10. 10. A selective valve operating apparatus comprising a structure adapted to be located in front of a group of valves and including power-operated frames, one of which is a supporting frame movable on a track extending in a course across the 20 front of the group of valves and another a supported frame movable in guides in the supporting frame, a valve operating device mounted on the supported frame and having a power-operated part adapted to engage and operate a valve 25 with respect to which it is aligned, said frames being relatively movable in different directions in order to locate said power-operated part in alignment with any valve in the group selected for operation, and remote control means operable from a station away from the structure and group of valves for controlling operation of the power-operated frames and power-operated part respectively.

11. 11. A selective valve operating apparatus comprising a structure adapted to be located in front of a group of valves and including relatively movable frames, one of which is a supporting frame and another a supported frame, a valve operating device mounted on the supported frame 35 and adapted, when operated, to engage and operate a valve with respect to which it is aligned, said supporting and supported frames being movable respectively in horizontal and vertical directions to locate said operating device in alignment 40 with any valve selected for operation in the group, power means for causing movement of the frames and operation of said device, comprising electric motors individual to each frame and to said device, and circuits with switches therein connected with the motors and having interlocking arrangement whereby the motors for the respective frames will be automatically rendered inactive when the motor for said device is active.

12. 12. A selective valve operating apparatus comprising an electric motor operated valve operating device adapted, when operated, to engage and operate a valve with respect to which it is aligned, an electric motor operated frame supporting said device and adapted, when operated, 50 to locate said device in alignment with any selected valve in a group of valves, and circuits with control switches therein connected with the motors of said device and said frame and having interlocking arrangement whereby the motor for 55 operating said device will be automatically rendered inactive when the motor for moving said frame is active.

13. 13. In combination with a relatively movable carrier and relatively movable valve operating 70 means mounted thereon and adapted to function to automatically engage and rotate a valve having a definite location with relation to the range of movement of the carrier, of electrically operated means for causing movement of the car- 75

rier to bring the valve operating means into and out of a position in which it will function to engage and rotate the valve, and having in electrical connection therewith electrically operated means for indicating the position of the carrier and hence the relation of the valve operating means with respect to the valve, electrically operated means adapted to cause functioning of the valve operating means, and remote control means operable from a station away from the carrier and valve for controlling the operation of both of the mentioned electrically operated means, said electrically operated indicating means being located in association with said remote control at such station.

14. The combination with a shaft having longitudinal movement and rotary movement, of an electric motor for driving the shaft, an electromagnetic operator for imparting longitudinal movement to the shaft, a remote station including a control switch, circuit connections for the motor and operator extending to the switch and which can be closed to actuate the motor and operator by the closing of the switch, an operable circuit-breaking device in the connections between the operator and the motor normally rendering the circuit through the motor inoperative, means controlled by the movement of the shaft longitudinally to a desired position for operating said device to render the motor circuit operative, and a governor rotated by the motor including mercury switch means connected in series with the motor to intermittently break the motor circuit at a pre-determined speed of the motor for regulating the rotation of the shaft.

15. Means for operating a wheel valve comprising an elongated valve engaging member, a support for the member movable to and from a position in which the member will be centered with respect to a valve, means for locking the support against movement in the position in which the member is centered, the member being mounted on the support to have longitudinal movement and rotary movement, means for moving said member in its longitudinal direction for causing its engagement and disengagement with a valve, means for rotating said member in either direction whereby to move the valve to and from its seat, said means for moving the member longitudinally and said means for rotating it being effective only when the support is locked against movement.

16. Wheel valve operating apparatus comprising a support and a fork mounted thereon for rotating and lengthwise movements and adapted to engage the spokes of a wheel valve, said fork being operatively disposed on the support in such manner that the rotating force applied thereby is transmitted to the spokes a spaced distance from the turning axis of the valve, and said fork having a lengthwise movement substantially greater than the movement of the valve to and from its seat, and means for regulating the pressure of the fork against the spoke in its rotating movement.

17. In a valve operating device, the combination with a frame and a shaft with an armature portion mounted on the frame to have rotative and longitudinal movements, of a solenoid on the frame cooperating with the armature portion and adapted, when energized, to move the shaft in one direction, resilient means resisting the movement of the shaft and adapted to re-position the same after each solenoid operation, an electric motor on the frame and gearing connections be-

tween the motor and shaft whereby to rotate the latter on energization of the motor and during longitudinal movement of the shaft.

18. In a valve operating apparatus, the combination of two movable frames, one of which is 5 wheel mounted to travel substantially horizontally on a track rail and the other of which is mounted in guides in the first frame to travel substantially vertically thereon, cable means and a counterweight for counterbalancing the second 10 frame, an electric motor connected with a traction wheel of the first frame and supplied with current by trolley lines for operating the first frame, a similar motor connected with said cable means and supplied with current by trolley lines 15 for operating the second frame, valve operating means projecting laterally from one side of the second frame, an electric motor and its circuit connected with the valve operating means whereby to operate the same, and control means including switches located at a remote station for controlling the operation of said respective motors and effective to render the motors for both of the frames inoperative when the motor for the valve operating means is operative. 25

19. In a valve operating apparatus, the combination of two relatively movable frames containing a common vertical plane about which they may be similarly placed, the second frame being supported upon the first, a device mounted on the 30 second frame and therewith movable and having a valve operating part operable laterally from one side of the common vertical plane, power means for each of the frames, power means for operating the valve operating part, means for 35 locking the two frames against movement at selected positions, and means operable from a remote station controlling the operation of the power means for each frame, the valve operating means and the locking means. 40

20. The combination with a shaft having an end portion adapted to cooperate with the wheel of a valve the stem of which is turnable for opening and closing the valve, of actuating means for reciprocating the shaft axially to cause it to 45 engage and disengage said end portion with the wheel, separate means for rotating the shaft in one direction to cause it to turn a valve to its seat and in another direction to cause it to turn the same to its open position, and means for 50 causing slowing up of the rotation of the shaft when the valve is a predetermined distance from its seat and also when the valve is a predetermined distance from its open position.

21. A valve operating device having, in combination, a frame, a shaft mounted therein to have longitudinal and rotary movements, means for reciprocating the shaft longitudinally, separate means for rotating the shaft, a plurality of longitudinally movable spring-held feelers on the 60 frame arranged in substantially parallel relation to the shaft, a sliding member connected with the shaft to move with the longitudinal reciprocating movements thereof and connected with the feelers to impart thereto longitudinal reciprocating movements by the shaft, and stop means for limiting the movements of the feelers in at least one direction. 65

22. In a wheel valve operating device, the combination with a member for rotating the valve, 70 of an electric motor and driven gear means between it and the member whereby to rotate the member, a normally open motor circuit and means for closing the same, a mercury switch supported for rotation in inclined position. means

for rotating the switch from the operation of the motor, said switch being connected in the motor circuit and having the characteristic of intermittently breaking the closed circuit at a predetermined speed of the rotating switch whereby to control the maximum speed of the motor and hence that of the valve rotating member.

23. The invention as defined in claim 22, in which the member for rotating the valve comprises a shaft having a forked end for engaging the wheel of the valve, and means for moving the shaft in its axial direction to engage its forked end with the wheel of the valve.

24. The invention as defined in claim 22, in which the member for rotating the valve comprises a shaft having an armature portion and an end in the form of a fork for engaging the wheel of the valve, and a solenoid in the motor circuit associated with the armature in such manner that it is adapted when energized by the closing of the circuit to draw the armature into its coil and move the shaft axially in a direction to engage the fork thereof with the wheel of the valve.

25. The invention as defined in claim 22, in which the member for rotating the valve comprises a shaft having an end portion shaped to engage the wheel of the valve, means for axially moving the shaft to engage its end portion with the wheel, a slide feeler movable longitudinally by the axial movement of the shaft, and resistance coils in the motor circuit cooperating with contacts on the feeler for regulating the amount of resistance in the motor circuit by the relative position of the feeler.

26. In combination, a shaft, means for moving the shaft axially toward a terminal of movement, a rotary device, an inclined mercury switch carried by said device and therewith rotatable, an electric motor, means driven by the motor for rotating said shaft and said rotary device, a motor circuit in which said switch is included, the characteristic of said switch being to intermittently make and break the circuit at a predetermined speed of the motor whereby to control the speed of rotation of the shaft as the latter approaches its terminal of movement.

27. In a valve operating device, in combination with a shaft mounted for bodily endwise and rotary movements, said shaft being separate from the valve and its stem and having means at one end thereof adapted to cooperate with a wheel on the valve stem, means for reciprocating the shaft endwise for effecting engagement and disengagement of its end means with the wheel, a reversible motor and its circuit, means including gearing between the motor and shaft for imparting rotary movement to the shaft, means under the control of the longitudinal movement of the shaft for causing reversal of the motor, and governor means driven by the motor and including an interrupter in the circuit for regulating the operation of the motor.

28. A valve operating device having, in combination a shaft disposed for longitudinal and rotary movements, means for reciprocating the shaft longitudinally, means for rotating the shaft in either direction, a plurality of longitudinally movable spring-held feelers arranged substantially parallel to the shaft, a sliding member connected with the shaft to move with the longitudinal reciprocating movements thereof and connected with the feelers to impart longitudinal reciprocating movements by the shaft, adjustable stops for limiting the movements of the feelers

in at least one direction, contacts on at least one feeler forming part of an electric circuit and arranged to be separated to break the circuit when the feeler engages its corresponding stop, contacts on at least one feeler forming part of the circuit and arranged to be engaged to close the circuit when the feeler engages its corresponding stop, and bridging contacts on at least one feeler forming part of a circuit and associated with contacts of series resistance coils and tripping coils whereby to vary resistance and to vary the number of turns in strength of the tripping coils when the feeler engages its corresponding stop, and said contacts being arranged to perform their respective functions during the rotation of the shaft.

29. Means for centering and locking a movable part on a center pin comprising a rock shaft on the movable part, a lever arm fixed on the shaft and adapted to engage one side of the pin, a second lever arm in which the shaft is longitudinally slidable adapted to engage the opposite side of the pin, said second lever arm adapted, when rocked, to rock the shaft, means for rocking the second lever arm and through it the shaft, in a direction to position the axis of both arms in a plane of the pin axis at opposite sides thereof, and means for subsequently moving the shaft longitudinally and thereby causing both arms to engage against the pin from opposite sides thereof.

30. In an object clamping device, the combination of two solenoids arranged at right angles to one another with their axis in different planes, a lever arm and a shaft slidable lengthwise therein and adapted to be rocked by the rocking action of said lever arm, means operated by the energization of one solenoid for rocking said lever arm and shaft in one direction, a second lever arm fixed to said shaft, and means operated by the other solenoid for moving said shaft lengthwise in a direction to bring said second lever arm in position to clamp an object between it and the first lever arm.

31. An object clamping device having, in combination, two lever arms adapted to clamp an object from opposite sides thereof, a shaft to which one arm is fixedly attached, slidable longitudinally in a keyway in the other arm, means for retaining the second arm from moving with the longitudinal movement of the shaft, and means for moving the shaft in a direction to draw the first arm toward the second arm.

32. A valve operating apparatus comprising a valve operating device, an upright propellable traveler, a rider carrying the valve operating device and mounted on the traveler for vertical operation, electric motor operated means controlling the operation of the rider, electric motor operated means controlling the propulsion of the traveler, and trolley feed lines for supplying said electric motors with current.

33. A valve operating apparatus having a motor-operated upright traveler mounted on wheels turning on a track rail, a motor-operated counterbalanced rider having its opposite ends slidably engaged in vertical ways in said traveler, two "selsyn" sets having their transmitting motors mounted respectively on the traveler and rider, the rotor of each set having a transmission therefor including reduction gearing and a pinion, a stationary gear rack with which the pinion of each transmission is engaged, the gear rack for the traveler being located parallel with the track rail while that for the rider is disposed on the traveler parallel with the path of movement of the rider, the reduction gearing in the transmis-

sion for the traveler set having a ratio such that the maximum travel permitted the traveler in either direction produces less than one revolution of its connected rotor, and the reduction 5 gearing in the transmission for the rider set having a ratio such that the maximum travel of the rider in either direction produces less than one revolution of its connected rotor.

34. A selective valve operating apparatus comprising a motor-operated traveler, a motor-operated rider on the traveler and a motor-operated valve operating device on the rider, circuits for the respective motors including manually operated switches, said circuits and switches being arranged in such interlocking relation that the switch controlling the circuit for operating the motor for the valve operating device can be placed in effective position only when the switches controlling the circuit for operating the traveler's 20 motor and the rider's motor, respectively, are in normal or ineffective positions.

35. The invention defined in claim 34, in which accurate centering and locking mechanisms are provided for the traveler and rider respectively 25 and operated electrically through connections connected through contactors with the circuit for the valve operating device motor and in such manner that when the switch controlling the circuit for causing operation of the latter is placed 30 in effective position the accurate centering and locking mechanisms will be operated to center and lock the traveler and rider, respectively, prior to effective engagement of the valve operating device proper with the valve to be operated thereby.

36. The invention as defined in claim 22, in which the member for rotating the valve comprises a shaft adapted to engage the wheel of the valve, means for axially moving the shaft to engage it with the wheel, a slide feeler connected 40 with the shaft for longitudinal movement by the axial movement of the shaft, resistance and tripping coils in the motor circuit, bridging contacts on the feeler and therewith movable, comprising a bridging contact in cooperation with the resistance coil for regulating the amount of 45 resistance in the motor circuit by the relative position of the feeler, and a bridging contact in cooperation with the tripping coil for varying by the relative position of the feeler the number of 50 turns in the tripping coil whereby to regulate the pressure with which the valve is closed against its seat by the shaft.

37. In combination, a valve operating device having a connected electric motor adapted, when 55 operated, to operate the device, a guided traveling frame supporting said device and its motor and having a connected electric motor adapted, when operated, to cause the travel of the frame, a remote station including switch mechanism, electrical systems associated with the switch mecha-

nism extending one to the motor for said device and the other to the motor for said frame, said systems being interconnected to establish flow of energy for operating the motor for said device when the switch mechanism is in one position 5 and for establishing flow of energy for operating the motor for said frame when the switch mechanism is in another position.

38. In a valve operating apparatus of the character described, a movable frame having a connected electric driving motor whereby to be moved, a valve operating device supported on the frame and having a connected electric driving motor whereby to be operated, a remote control station including electrically interlocking switch 10 mechanism, with electrical transmission systems extending to said motors, and, according to the connective relation of the switch mechanism, automatically effective to establish an electrical circuit through the driving motor for said frame 15 only when there has been disestablishment of the electrical circuit through the driving motor for said device, and vice versa.

39. A valve operating apparatus comprising a traveler, a rider operatively supported on the traveler, a valve operating device supported on the rider, electric driving motors individual to said traveler, rider and device, a remote control station and electrical make and break systems having connection with each of said driving motors, and actuatable switches at said station interlocking connected with said systems, by the actuation of which each of said driving motors 30 may be independently operated.

40. In a valve operating apparatus having a movable frame operated by a connected electric driving motor and a valve operating device supported on the frame and operated by a connected electric driving motor, the combination of interconnecting transmission circuits for the driving motors including interlocking switches manually operated from normal to effective positions and automatically returnable from effective to normal positions, a holding coil with interconnecting circuit therefor for the switch controlling the motor connected with the valve operating device, to hold said switch against returning to normal position until said coil is de-energized, means in connection with the circuits for rendering the second switch electrically inoperative in effective position at all times when the first-named switch is held by its holding coil, and electrical means included in the circuits, depending for action upon a pre-determined position of the valve operating device, for tripping 45 the holding coil circuit and consequently de-energizing the holding coil to permit automatic return of the first-named switch to normal position.
